UNITED STATES PATENT OFFICE.

FERDINAND FRANK, OF SUISUN, CALIFORNIA.

DRAWER-PULL.

SPECIFICATION forming part of Letters Patent No. 289,245, dated November 27, 1883.

Application filed August 4, 1883. (No model.)

To all whom it may concern:

Be it known that I, FERDINAND FRANK, of Suisun, in the county of Solano and State of California, have invented certain new and useful Improvements in Box-Pulls; and I do hereby declare the following to be a full, clear, and exact description of the invention, such as will enable others skilled in the art to which it appertains to make and use the same.

10 My invention relates to an improvement in box-pulls, the object being to provide a cheap and simple device adapted to be attached to pasteboard and other boxes or drawers, for the purpose of affording a convenient handle for withdrawing them from shelves.

15 With this object in view my invention consists of a strip of sheet metal, having one or more prongs adapted to be passed through one face of the box to which it is to be applied, and 20 to be bent against the inside thereof.

25 In the accompanying drawings, Figure 1 is a perspective view of a box provided with a pull constructed in accordance with my invention. Fig. 2 is a plan view thereof. Fig. 3 is a view showing another manner of securing my improved device in position; and Fig. 4 represents several modified forms which my invention may assume.

30 A represents the handle, provided with the prongs b. In adapting the same to use the prongs b are passed through the bottom of the box and turned down against the same, leaving the handle A projecting from the end of the box, as shown in Fig. 1.

35 When desired, the form of construction may vary. For use on large boxes or drawers, or boxes of strong material, I employ a pull consisting of handle A, with the prong d, as shown in Fig. 2.

40 My device can also be fastened to the front end of a box or drawer. A pull designed principally for this purpose is shown in Fig. 3. It consists of a metallic strip having a handle, A, and prongs B, the same being cut so 45 as to form intermediate shoulders, e, which

latter limit the penetration of the prongs. In attaching this device I pass the prongs B through the front end of a box or drawer, and secure it therein by bending them in opposite directions, thus forming a strong and sufficient hold. The function of the shoulders e is to prevent the handle from entering the box.

50 My improved drawer-pull is cheap, ornamental, and durable. It is adapted to be easily and securely attached to a box or drawer, and it can be utilized more than once, as it may readily be removed from one box and attached to another.

55 I do not confine myself to any particular form of construction, as the handle may be crimped or perforated to afford a better hold than that offered by a smooth handle. It may also be cut in various shapes and forms for ornamental purposes. The handle may be covered with cloth, paper, or any other desired material.

60 I am aware that metallic fasteners have been made of sheet metal with two prongs, located at right angles to the head of the fastener. I am also aware that suspension rings 70 have been made with attaching prongs, and hence I make no claim to such improvements.

Having thus described my invention, what I claim as new, and desire to secure by Letters Patent, is—

75 The combination, with a box, of a box-pull made from sheet metal, and consisting of the broad handle portion A, having prongs that extend through and are bent back against the inner surface of the box, while the handle portion A projects in front of the box, substantially as set forth.

80 In testimony whereof I have signed this specification in the presence of two subscribing witnesses.

FERDINAND FRANK.

Witnesses:

WILLIAM WOLF,
M. A. MAYNARD.
